Attorney.

UNITED STATES PATENT OFFICE.

ISRAEL E. HELLER, OF BUFFALO, NEW YORK.

CLOTH-FINDINGS DISPENSER.

1,416,293.

Specification of Letters Patent. Patented May 16, 1922.

Application filed January 12, 1921. Serial No. 436,728.

To all whom it may concern:

Be it known that I, ISRAEL E. HELLER, a citizen of the Republic of Poland, residing at Buffalo, in the county of Erie and State 5 of New York, have invented certain new and useful Improvements in Cloth-Findings Dispensers, of which the following is a specification.

My invention relates to cloth findings dispensers, and more particularly to a device in which small pieces of cloth of uniform outline are arranged in a systematic manner so that they can be conveniently removed one at a time, as needed.

15 In clothing factories, shirt factories, and other similar establishments, it is necessary in the make-up of garments to utilize small similarly-shaped pieces of cloth. For example, in clothing factories, pockets, pocket 20 facings and other parts of a coat, trousers or other garment are sewed in place by an operative, who, under the present mode of operation, takes one piece of cloth from a stack of pieces placed loosely upon a table, 25 and in view of the fact that these operations are hurried, the operative oftentimes unknowingly grasps more than a single piece, with the result that during the course of a day many pieces fall upon the floor and are 30 wasted. The same is true in shirt factories with interlinings for cuffs and collars, and oftentimes quite a number of these are accidentally switched onto the floor with the 35 result that during the course of a year a considerable loss results from the waste of such small although valuable pieces, due to these pieces, when on the floor, being swept out with the accumulated waste.

It is one of the objects of my invention to 40 provide a device in which small similarly-shaped pieces used in the construction of garments may be placed within a container in a systematic manner and be removed therefrom, one at a time, through an opening 45 within one of the walls of the container.

A further object of my invention is to 50 provide a device of this kind which can be attached to the under side of a table, machine, or the like, within convenient reach 55 of the operative so that in sewing these pieces to other pieces or onto portions of a garment, they can be handily reached without loss of time and with assurance that all remaining pieces will be left within the container for use as needed.

A further object of my invention is to provide a device of this kind in which small pieces of cloth folded together in zigzag form and adapted to be used in the construction of garments are placed within the container with layers of adjoining pieces interfolded and with the bottom layer of the lowermost piece passed through an opening 60 formed in one of the walls of the container so that upon drawing the lowermost piece of 65 the stack from the container, it will automatically draw out a portion of the adjoining piece so that it may also be conveniently withdrawn from the container when needed.

A further object of my invention is to provide a device of this kind constructed to permit of readily inserting a stack of small pieces of cloth thereinto.

With these and other objects in view the invention consists in the novel features of 75 construction and in the arrangement and combination of parts to be hereinafter described and more particularly pointed out in the subjoined claims.

In the drawings:—

Fig. 1 is a perspective view of my improved device.

Fig. 2 is a vertical section through the same.

Fig. 3 is a cross section taken on line 3—3, 85 Fig. 2.

Fig. 4 is a bottom plan view of the device.

Fig. 5 is a view showing two pieces of cloth folded in zigzag form and interfolded, with the layers thereof slightly separated.

Reference being had to the drawings in detail, like numerals refer to like parts in the several figures.

95 The device comprises a container which is of box-like formation and includes a body portion 6 provided with side walls 7, 8, 9 and 10 and a bottom wall 11, the side walls 7 and 10 having outwardly-directed flanges 100 12 at their upper ends which are provided with screw holes 13 through which screws 14 are passed that take into a table top 15 or the like. Said body portion is open at its upper end, as at 16, and has an opening 17 extending from the lower edge of the side wall 10, which is comparatively short, to the edge of the bottom 11, which terminates in a plane approximately centrally between the walls 7 and 10. This 110

opening may therefore be referred to as an oblique opening formed in the body portion.

Hinged to the lower edge of the short side wall 10 is a closure 18, which may be said to have an outer wall 19 alined with the short side wall 10 of the body portion, a bottom wall 20 alined with the bottom wall 11 of said body portion but spaced therefrom to form an opening 21 through which the material within the container is to be withdrawn, and side walls 22 which are gradually widened downwardly so as to fully close the sides 8 and 9 of the body portion having their walls cut obliquely. The side walls 22 of the closure overlap the side walls 8 and 9 of the body portion and to each side wall 22 a hook-shaped keeper 23 is pivotally secured which is adapted to be hooked over an outstanding pin 24 on the corresponding side wall of the body portion.

25 designates the small pieces of cloth which are placed within the container and adapted to be removed therefrom one at a time. These small pieces of cloth are of uniform outline and are folded into zig-zag form, as clearly shown in Figs. 2 and 5 to provide three layers 26, 27, 28. The layers 26 and 28 may be termed outer or end layers while the layer 27 may be termed an intermediate layer. The outer or end layers of each piece of cloth are folded between the adjacent end and intermediate layer of the adjoining piece of cloth, and these pieces 30 so folded and inter-folded are arranged in stacks and may be tied together so as to form a bundle. The stack of cloth pieces within the container are pressed together by a flat weight 29 suspended centrally from a cord 30 or other flexible device hooked or otherwise fastened to a cross member 31 extending from or fastened to opposite walls of the container. This cross member in preferred form comprises a wire having a loop 32 formed midlength thereon, opposite ends of the wire being passed through openings 33 in opposite walls and having their terminals bent at an angle thereto, as at 34, so as to be retained in position with the loop 35 centrally within the container. The flat weight 29 rests upon the stack of cloth pieces and lowers as the pieces become used, the cord or other flexible means 30 being of a length to permit the weight to reach 40 a point close to the bottom of the container.

When inserting the piece of cloth into the device, the cover 18 is swung upwardly on its hinge after unhooking the keepers 23. A bundle of pieces is then inserted in the body portion of the container. The tie for holding the same in bundle form can then be removed, after which the weight 29 is properly positioned on the stack of cloth pieces so assurance will be had that these 45 pieces will be automatically fed to the bot-

tom as one piece after the other is removed. After positioning the stack of cloth pieces within the body portion and positioning the weight, the closure is swung downwardly to close the oblique opening in said body portion and when closed the front wall 19 and side walls 22 of the closure serve as continuations of the side walls 8, 9 and 10 of the body portion while the bottom 20 of the closure assists the bottom 11 of the body portion to properly support the stack of cloth pieces.

When placing the bundle of pieces in the container and removing the tie, which may be a string, a piece of paper or other suitable device readily separable and capable of being withdrawn from its position around the pieces of cloth, the lower layer of the bottom piece of cloth will immediately hang over the edge of the bottom 11 of the body portion and when closing the closure this hanging portion will extend through the opening 21 between the edge of said bottom wall and the edge of the bottom wall 20 of said closure.

When a piece of cloth is required in the construction of a garment, the operative grasps the portion of the piece of cloth extending through the opening 21 and pulls the complete piece out, with the result that the end layer 28 of the adjoining piece will be drawn out through the opening 21 and will be in position to be grasped by the operative when another piece of cloth is needed.

Having thus described my invention, what I claim is:—

1. A cloth findings dispenser, comprising a box-like structure open at its upper end and provided with outstanding securing flanges at said end, said box-like structure being adapted to be secured to the under side of an object and having an opening at its lower end through which pieces of cloth findings folded and inter-folded are adapted to be withdrawn one at a time, and means within said box-like structure for pressing the pieces of cloth findings against the bottom of said box-like structure.

2. A device of the kind described, comprising a body portion having three full length side walls, a short side wall, a bottom terminating in a plane between said short side wall and the side wall directly opposite and an opening extending from the edge of said bottom to the lower edge of said short side wall, a closure hinged to the lower edge of said short side wall and having a front wall in line with said short side wall, a bottom wall in line with the bottom of said body portion and downwardly widened side walls, the whole being arranged to form a box-like structure in which the bottom of said body portion and the bottom of said closure serve to support a stack of cloth findings placed therein, and means to press 130

downwardly against said stack of cloth findings.

3. A cloth findings dispenser, comprising a body portion having an oblique opening 5 extending from a point near its upper end to the bottom thereof, and a downwardly widened closure hinged to the body portion at the upper end of said oblique opening, said body portion having a bottom and said 10 closure having a bottom spaced from said first-mentioned bottom, said dispenser so formed having a stack of cloth findings comprising individual pieces folded and inter-folded with one end of the lowermost 15 piece projecting through the space between said bottoms, and means for pressing said layer of cloth findings downwardly against said bottoms.

4. A cloth findings dispenser having side 20 walls and a bottom wall provided with an opening and having an open top, and means to secure said dispenser to the under side of an object so as to close said top.

5. A cloth findings dispenser comprising 25 a box-like structure open at its upper end and provided with means at its upper end for fastening the same to the under side of

an object, opposite walls of said box-like structure having openings near their upper ends, and a cross member having its ends 30 retained in said openings and being provided with a loop midlength thereof, a flexible element secured to said loop, and a weight secured to the lower end of said flexible element.

35 6. A cloth findings dispenser, comprising a box-like structure having means at its upper end for securing the same to the under side of an object and having an opening at its bottom for the successive removal of 40 pieces of cloth findings stacked within said structure, a cross member formed of wire extending through opposite side walls and having bent terminals at the outer sides of said walls and a loop midway between said 45 side walls, a flexible element secured to said loop, and a weight secured to said flexible element and adapted to automatically lower as the pieces of cloth findings are successively withdrawn from the box-like structure.

50 In testimony whereof I affix my signature,

ISRAEL E. HELLER.
